GAS ANALYSIS APPARATUS

Wladimir M. Zaikowsky, Pasadena, Calif., assignor to Nina D. Zaikowsky

Application November 22, 1944, Serial No. 564,645

7 Claims. (Cl. 73—27)

1

This invention relates to the analysis of gaseous mixtures by thermal-conductivity measurements and is particularly useful in connection with the analysis of products of combustion of hydrocarbon fuels or coals for the purpose of determining the ratio of fuel to air.

Some difficulty has been encountered with known methods of analyzing products of combustion by thermal-conductivity (hereinafter referred to as T. C.) measurements because although oxygen of the atmospheric air used for combustion combines with the fuel to form water and carbon dioxide, heretofore it has been proposed to eliminate the water before conducting the exhaust gas to the T. C. cells. The elimination of the water from measurement is objectionable when the ratio of carbon to hydrogen in the fuel varies as it frequently does in different gasolines and other fuels, both liquid and solid. Conventional T. C. apparatus adjusted to show theoretical mixture with a fuel of one H/C ratio will give an erroneous reading with a fuel of a different H/C ratio, because the percentages of carbon dioxide in the exhaust will be different with the different fuels for said theoretical mixture. This is because conventional apparatus indicates only the amount of carbon dioxide formed in combustion, and thus the amount of oxygen consumed in the formation of water of combustion remains unaccounted for. Heretofore the apparatus usually was not adapted for the measurement of the water of combustion in vapor form within the cell; besides water and carbon dioxide have opposite effects on the T. C. of exhaust and so obscure each other. Furthermore, the water in the exhaust includes not only water of combustion but also water of atmospheric humidity, and, without special correction, the error resulting from the presence of atmospheric humidity can become very serious.

An object of the present invention is to determine, by T. C. measurements, changes in the total percentage of combined oxygen in the exhaust resulting from combustion of a hydrocarbon fuel and air.

Another object is to provide T. C. exhaust analysis apparatus, the accuracy of which is at least approximately immune to variations in H/C ratio of the fuel being burned.

Another object is to account for, in T. C. measurements, that portion of the water in exhaust gas that is water of combustion as distinct from that portion that is due to humidity of the air of combustion.

Another object is to determine, by T. C.

2

measurements, the sum quantity of two components having opposite effects on the thermal-conductivity of a gas mixture.

Another object is to reduce contamination of T. C. cells in the analysis of exhaust gas.

Other more specific objects and features of the invention will appear from the detailed description to follow.

In accordance with the invention, I determine the sum of two antagonistic effects produced by different components of a gaseous mixture, such as water vapor and carbon dioxide in exhaust gas by making their effects additive in the measuring circuit. One way of doing this is to supply the gas containing the two constituents to a cell of unit sensitivity in one arm of a Wheatstone bridge and simultaneously apply a dried portion of the gas to a cell of substantially double sensitivity in an adjacent arm of the bridge. The effect of carbon dioxide in the second arm of the bridge will be substantially double that in the first arm, and there will be no effect of the water vapor in the second arm. The overall effect of carbon dioxide and water on the bridge circuit will be substantially equivalent to the arithmetic sum of the opposite effects (on thermal-conductivity of exhaust gas) produced by the water vapor and carbon dioxide present. This effect will be substantially proportional to the total volume of oxygen consumed by the hydrocarbon fuel in the formation of the carbon dioxide and water.

It is well established that in atmospheric air, the proportion of oxygen is substantially constant, and, therefore, with apparatus operating in the manner stated above, it is possible to determine, with accuracy adequate for many practical purposes, whether air-fuel mixtures are theoretical or lean, irrespective of variations in the H/C ratio of the fuel. Thus, the above described system is applicable for measurement of the oxygen consumed in combustion of lean or theoretical air-fuel mixtures since the free oxygen in lean exhaust has approximately the same thermal-conductivity as nitrogen.

Obviously, the exhaust of rich air-fuel mixtures will contain besides carbon dioxide and water, other constituents such as free carbon, carbon monoxide, hydrogen and other hydrocarbons, and the proportions of these constituents in the exhaust of a rich mixture will be dependent on the nature of the hydrocarbon fuel used. In order to extend the described method of T. C. analysis to rich mixtures, I propose to subject the exhaust to a pre-treatment by a non-gaseous

oxidizing agent such as copper oxide. Such treatment has no lasting effect on lean exhaust but converts rich exhaust into a gas composed substantially of only nitrogen, carbon dioxide and water vapor.

In exhaust treated with hot copper oxide, the sum percentage of carbon dioxide and water will increase when the mixture becomes rich (because more carbon and hydrogen will be oxidized, whereas the amount of nitrogen will remain substantially the same) and the sum percentage of carbon dioxide and water will decrease when the mixture becomes lean (because the amount of nitrogen will remain substantially the same and there will also be free oxygen present, whereas there will be less carbon and hydrogen to be oxidized). Thus, through the use of treatment of exhaust gas by a non-gaseous oxidizing agent, I extend the described method of T. C. analysis for the indication of both rich and lean air-fuel mixtures.

The method so far described is imperfect in that any water present in the air of combustion as humidity is indicated as water of combustion. To eliminate errors due to atmospheric humidity, I employ the following procedure.

I supply exhaust gas to a first cell of unit sensitivity in one arm of the bridge at a pressure low enough to maintain all the water originally present in the gas in vapor phase, and supply atmospheric air at the same low pressure to a cell of unit sensitivity in an opposite arm of the bridge. The effect of atmospheric humidity on the second cell neutralizes the effect due to atmospheric humidity in the first cell with sufficient accuracy for many practical purposes.

I also provide additional cells of double sensitivity in both arms of the bridge in series with the first-mentioned cells. The double sensitivity cell in the first arm is supplied with atmospheric air saturated with water vapor. The double sensitivity cell in the second arm is supplied with exhaust gas at atmospheric pressure so that some of the water in the exhaust gas condenses and the effect of the water in the exhaust gas on the cell is that of water vapor of saturation, which effect is cancelled by the water-saturated air in the double sensitivity cell in the first arm. The double sensitivity cell in the second arm is, therefore, really responsive only to the carbon dioxide in the exhaust, and since the cell is of double sensitivity, it cancels the effect of carbon dioxide in the first low pressure cell. The overall result is that the balance of the bridge is determined by the arithmetical sum of the T. C. effects of the carbon dioxide and water of combustion in the exhaust gas.

A full understanding of the invention may be had from the following detailed description with reference to the drawing, in which:

Fig. 1 is a schematic diagram of one system in accordance with the invention; and

Fig. 2 is a schematic diagram of a modification of the system shown in Fig. 1.

Referring first to Fig. 1, there is disclosed a bridge circuit having two T. C. filaments 10 and 11 arranged in series in one arm and two T. C. filaments 12 and 13 arranged in series in the opposite arm. The bridge is completed by fixed resistance arms 14 and 15 and a resistor 16 having an adjustable tap thereon, the latter constituting one end of one diagonal of the bridge. A meter 17 is connected between the movable contact and the juncture of the two arms containing the filaments. A battery 18 is connected

in series with the variable resistor 28 in the other diagonal of the bridge.

As shown in Fig. 1, exhaust gas is supplied in series to all of the filaments. Thus it enters 5 through a conduit 19, passes through a constriction 29 and into a treating cell 20 containing heated copper oxide or other oxidizing agent for the purpose of completely burning all fuel and preventing the entry of raw fuel into any of the 10 T. C. cells. Heat may be provided in any known way but an electric resistor 60 energized by a battery 61 is illustrated. From the treating cell 20 the gas flows through a conduit 21 past a cell containing filament 10, thence through a drying 15 cell 22 which abstracts moisture therefrom. Thereafter it flows through a conduit 23, past cells containing filaments 12 and 13 and through a treating cell 24 which absorbs carbon dioxide from the gas. Thereafter it flows through a conduit 25, past a cell containing filament 11 to an 20 exhaust pump 27 which is of sufficient capacity to maintain a relatively low pressure on the down stream side of the restriction 29. The pressure should be kept low enough to maintain all 25 of the water present in the exhaust gas in the vapor phase.

Each cell containing one of the filaments 10 to 13, inclusive, is connected to the adjacent portion of the conduit, preferably by a diffusion passage, so that interchange of gas will take place 30 between the conduit and the cells without objectionable currents in the cells.

In my copending patent application Serial No. 477,675 filed March 1, 1943, I have described and 35 broadly claimed systems involving such supply of exhaust gas at low pressure to the test cells and systems employing such diffusion passages leading to the test cells.

In the system of Fig. 1, variations in the 40 resistance of the filament 10 are determined by changes in the T. C. of the gas in the cell, which in turn is chiefly determined by changes in the carbon dioxide and water vapor present in the exhaust. Changes in the resistance of filaments 45 12 and 13 are determined chiefly by changes in the amount of carbon dioxide present in the exhaust. Changes in the resistance of filament 11 are minor and are determined by changes in all 50 constituents other than water and carbon dioxide.

Let it be assumed that in the absence of any 55 cooling effect due to T. C., the resistances of all the filaments would be equal and the bridge balanced. Then in operation the balance tends to be upset because of the different T. C.'s of the different gases in the different cells; thus:

$$R_{10} \text{ is a function of } A-B+C$$

$$R_{12} \text{ is a function of } A-B$$

$$R_{13} \text{ is a function of } A-B$$

$$R_{11} \text{ is a function of } A$$

Where:

$$R_{10} \text{ is the change in resistance of filament 10 due to T. C.}$$

$$R_{12} \text{ is the change in resistance of filament 12 due to T. C.}$$

$$R_{13} \text{ is the change in resistance of filament 13 due to T. C.}$$

$$R_{11} \text{ is the change in resistance of filament 11 due to T. C.}$$

$$A \text{ is the T. C. of components other than water and carbon dioxide}$$

$$B \text{ is the T. C. of carbon dioxide}$$

$$C \text{ is the T. C. of water vapor}$$

The net effect on the balance of the bridge is obtained by adding the resistance changes in one arm of the bridge and subtracting those in an adjacent arm since an increase of resistance in one side deflects the meter in the same direction as does a decrease in the other arm. Thus:

$$\begin{aligned}\text{Unbalance} &= R_{10} + R_{11} - R_{12} - R_{13} \\ &= (A - B + C) + (A) - (A - B) - (A - B) \\ &= A - B + C + A - A + B - A + B \\ &= B + C\end{aligned}$$

Hence, the net effect of the system is to produce an indication proportional to the arithmetic sum of the separate effects of water and carbon dioxide. One molecule of oxygen (O_2) combines with carbon to produce one molecule of carbon dioxide (CO_2) and combines with hydrogen to produce two molecules of water ($2H_2O$). However, the effect of a small change in the percentage of carbon dioxide on the thermal-conductivity of exhaust is substantially equal in magnitude to the effect produced by twice the change in the percentage of water vapor. Thus in "Gas Analysis by Measurement of Thermal-Conductivity" by H. A. Daynes, on page 119 in Table 17, it is stated that the relative deflections per 1% change of carbon dioxide and water vapor, respectively, are -0.132 and +0.067 where the deflection produced by 1% change of hydrogen content in air is taken as equal to +1.000.

As a result, the system of Fig. 1, when once balanced for theoretical mixture of one hydrocarbon fuel and air, will also be approximately balanced for theoretical mixture of any other hydrocarbon fuel and air because substantially the same effect is produced on the system by the carbon dioxide resulting from combination of one molecule of oxygen with carbon as by the water vapor resulting from combination of one molecule of oxygen with hydrogen.

It is to be understood that it is not essential or even preferable to conduct a single stream of gas past all the cells. The gas can be divided into parallel streams and treated separately, it being merely necessary to deliver untreated gas to filament 10, dried gas to filaments 12 and 13, and gas dried and treated to remove carbon dioxide to filament 11. It may be desirable to employ parallel flow in some instances to prevent lag in the arrival of gas to some cells with respect to other cells, or to prevent different pressures in different cells.

Obviously, a single cell having a filament of double length can be substituted for the two cells 12 and 13.

The present invention utilizes the fact that the effect of water vapor is opposite to that of carbon dioxide in T. C. apparatus, whereas all previous attempts have been in the direction of eliminating either the carbon dioxide or the water so that one would not obscure the effect of the other.

The system of Fig. 1 has the defect that it does not distinguish between water of combustion and water that was present as humidity in the air of combustion. Hence it would correctly indicate theoretical mixture only so long as the atmospheric humidity did not change.

Fig. 2 shows a system that is not only balanced for theoretical mixture of fuels having different H/C ratios but also compensates for atmospheric humidity, and thus the balance of the bridge is not affected by changes in atmospheric humidity. This system employs the same general bridge arrangement as that of Fig. 1 but has two T. C. 75 changes in resistance due to T. C. and reversing

filaments 30 and 32 of equal sensitivity in opposite arms of the bridge and two T. C. filaments 31 and 33 of double sensitivity (i. e., filaments twice as long) in opposite arms, the filament 31 being in the same arm with filament 30, and filament 33 being in the same arm with filament 32. Exhaust gas to be tested enters through a conduit 43 and passes through a cell 20a corresponding to the cell 20 of Fig. 1 which contains copper oxide or other oxidizing agent for preventing any unburned fuel from reaching the cells. The gas leaves the treating cell 20a through a conduit 45, which conducts the main stream of the gas past the filament 31 and is transferred to the cell containing the filament by diffusion. A portion of the gas from conduit 45 is drawn through a restriction 46 into a conduit 47 which is connected by a diffusion passage to the cell containing filament 32. The gas is drawn through the conduit 47 and maintained at a suitable low pressure at which all water remains in the vapor phase, by a pump 54 and a constant pressure valve 49. The pump and valve also maintain a flow of atmospheric air at low pressure through a restriction 50 into a conduit 51 connected by a diffusion passage to the cell containing filament 30. The last filament 33 is positioned in a cell containing air and connected to a closed chamber 52 containing a body of water 53 so that the filament 33 is at all times exposed to air saturated with water vapor.

It will be apparent from an inspection of Fig. 2 that filament 30 is exposed to atmospheric air at low pressure and filament 32 is exposed to the exhaust gas at low pressure, whereas filament 31 is exposed to exhaust gas at substantially atmospheric pressure and filament 33 is exposed to air saturated with water vapor. The conduit 45 supplying exhaust gas at atmospheric pressure to the filament 31 is of such length that the gas therein has opportunity to cool to atmospheric temperature so that some of the water vapor therein condenses and the gas to which filament 31 is exposed is saturated with water vapor substantially at the same temperature as the air filling the cell 33.

In the operation of the system of Fig. 2, the resistances of the different filaments are affected by the T. C.'s of the gases to which they are exposed in the following manner:

$$\begin{aligned}R_{30} &\text{ is a function of } C_h \\ R_{32} &\text{ is a function of } -B + C_c + C_h \\ R_{31} &\text{ is a function of } 2(-B + C_s) \\ R_{33} &\text{ is a function of } 2(C_s)\end{aligned}$$

Where:

60 R_{30} is the change in resistance of filament 30 due to T. C.

R_{32} is the change in resistance of filament 32 due to T. C.

R_{31} is the change in resistance of filament 31 due to T. C.

65 R_{33} is the change in resistance of filament 33 due to T. C.

B is the T. C. of carbon dioxide

C_c is the T. C. of water vapor of combustion

70 C_h is the T. C. of water vapor of atmospheric humidity

C_s is the T. C. of water vapor saturation

Adding the components that determine the 75 changes in resistance due to T. C. and reversing

the signs of the components in the right half of the bridge, we have

Unbalance

$$\begin{aligned}
 &= R_{30} + R_{31} - R_{32} - R_{33} \\
 &= (C_h) + 2(-B + C_s) - (-B + C_c + C_h) - (2C_s) \\
 &= C_h - 2B + 2C_s + B - C_c - C_h - 2C_s \\
 &= -B - C_c
 \end{aligned}$$

It will be observed that the deflection is, therefore, a function of the concentration of carbon dioxide plus that portion of the water vapor concentration that is due to water of combustion.

In other words, the resistance of filament 32 is a function of the concentration of carbon dioxide and of all the water vapor present in the exhaust. The resistance of filament 30 is a function only of the water vapor due to air humidity, and, since it is in the opposite arm of the bridge from filament 32, it cancels the effect of atmospheric humidity on filament 32, leaving the latter effective to show the difference between the T. C. of the carbon dioxide of combustion and the water of combustion. The resistance of filament 31 is a function of the carbon dioxide concentration in the exhaust and the water of saturation. Since filament 33 is exposed to water vapor of saturation, it compensates for the effect of the water on filament 31, leaving the latter effective only to show the concentration of carbon dioxide. Since filament 31 is twice the length of filament 32, it neutralizes the effect of carbon dioxide on the filament 32 and produces an effect responsive to the carbon dioxide, which effect is additive with respect to the effect on filament 32 of the water vapor of combustion.

Aside from other considerations, the system of Fig. 2 has the practical advantage over that of Fig. 1 of eliminating the need of desiccants for drying the gas and reagents for removing the carbon dioxide.

It is to be understood that equations have been used for explaining the operation because they afford a simple and understandable method of describing what takes place, and not to indicate or infer great precision of results. Oftentimes, the thermal-conductivities of gaseous mixtures do not follow the simple rule of proportions.

Thus, the correction for atmospheric humidity will be more accurate when the volume of water resulting from combustion is small than when it is large. According to the book of H. A. Daynes previously referred to, page 112, the increase in thermal-conductivity resulting from 1% increase in water vapor decreases as the total water vapor concentration increases up to about 20%, and becomes negative thereafter. My own measurements indicate that the increase in the T. C. of exhaust gas due to atmospheric humidity is greater than the increase in the T. C. of the atmospheric air due to that humidity. For this reason, if the atmospheric air contains say 2% water vapor and the exhaust contains 15% water of combustion, the compensation for atmospheric humidity of the system of Fig. 2 will be more accurate than one might expect it to be from the graphs shown in the above quoted reference for moist air, because the presence of carbon dioxide in exhaust increases the increment of T. C. corresponding to unit change in water vapor concentration.

An example will illustrate how important it is to compensate, even imperfectly, for atmospheric humidity: According to Daynes, atmospheric humidity equivalent to 2% of water vapor by vol-

ume changes the T. C. nearly as much as 1% of carbon dioxide would. Inasmuch as the exhaust of a lean mixture will contain not more than 8% carbon dioxide by volume, failure to correct for the atmospheric humidity can introduce an error of about 12% in case the fuel contains no hydrogen. On the other hand, if the fuel contains one gram mole of hydrogen for each gram atom of carbon, the exhaust will contain approximately 8% carbon dioxide and 8% water vapor of combustion, by volume. Since the water vapor has approximately half the effect on T. C. and acts oppositely, the magnitude of the effect on T. C. is substantially that of 4% dry carbon dioxide or .8% of water vapor alone. In such a case, failure to correct for 2% water vapor due to atmospheric humidity can introduce an error of 25%.

It will be apparent that when the sensitivities of resistors 31 and 33 are similar to the sensitivities of resistors 30 and 32, the apparatus illustrated in Fig. 2 becomes suitable for the measurement of the total water resulting from complete combustion of the fuel. Thus, this apparatus provides for the indication of the air-fuel ratio supplied to a combustion device utilizing definite hydrocarbon fuels just as such air-fuel ratio is determinable from the measurement of the carbon dioxide alone. Therefore, the invention is also useful for determining air-fuel ratio by measuring the percentage of the water of combustion alone.

In Fig. 1 the resistors 10, 11, 12 and 13 are shown placed within cells 10a, 11a, 12a and 13a, respectively. The arrangement is such that the walls of each related pair of cells (cells 10a and 12a constituting one pair and cells 11a and 13a constituting the other pair) or all of said cells are kept at equal temperatures by forming them in a metal block or blocks. In Fig. 1 the distances between the cells 13a and 12a and between cells 11a and 13a are shown disproportionately large for the sake of clearness of illustration, but in actual practice the cells are preferably placed as close to each other as is practicable.

Similarly, in Fig. 2, the filaments 30, 31, 32 and 33 are positioned within cells 30a, 31a, 32a and 33a, respectively, and the walls of the cells are preferably kept at the same temperature for respective pairs or for all of said cells by forming them in a metal block.

It is understood that in the system of Fig. 1, the arrangement is such that on the up-stream side of the restrictors 29 the gas remains at a temperature sufficiently high to maintain all water in the vapor phase at atmospheric pressure, but before the exhaust gas reaches any cell, it is preferably cooled to the substantially lower temperature of the walls of the cells (which may be kept at atmospheric temperature). This insures that no water is condensed from the exhaust on the up-stream side of the restrictor.

It is also to be understood that in the system of Fig. 2, the temperatures along the gas conduits, including portions 43 and 45, are such that no condensation of water or unburned fuel occurs on the up-stream side of the restrictor 46, so that the filament 32 is exposed to exhaust containing all the carbon dioxide and all the water that resulted from the combustion of the fuel.

It is also to be understood that the reaction chamber 20 in Fig. 1 or 20a in Fig. 2 can be posi-

tioned on the upstream side of the restrictor, and this arrangement may be advantageous in that it permits utilization of the cooling resulting from the expansion of the gas across the restrictor 29 for dissipation of the heat acquired by the gas in the reaction chamber.

Where in the claims a hydrocarbon fuel is referred to, the expression is intended to include fuels which may contain free carbon and/or free hydrogen in addition to hydrocarbon compounds.

Various departures from the exact system shown and described in detail can be made without departing from the invention, which is to be limited only to the extent set forth in the appended claims.

I claim:

1. Apparatus of the type described, comprising: first and second thermal-conductivity cells of equal sensitivity and third and fourth thermal-conductivity cells having sensitivities approximately twice that of the first cell; means for supplying exhaust gas to be analyzed to said second cell at a sub-atmospheric pressure low enough to maintain all water in said exhaust gas in the vapor phase; means for supplying atmospheric air to said first cell at said sub-atmospheric pressure; means for supplying exhaust gas to said third cell at such pressure that water saturation results; means for supplying air saturated with water vapor to said fourth cell; and bridge means for comparing the combined resistance of the first and third cells against the combined resistance of the second and fourth cells, whereby said first cell cancels the effect of atmospheric humidity on said second cell, said fourth cell cancels the effect of water vapor in said third cell, and said third cell cancels the effect of carbon dioxide in the second cell and produces an equal effect in additive relation to the effect of water vapor in said second cell.

2. Thermal-conductivity apparatus comprising: a bridge circuit including in one arm a first cell; means to supply to said first cell exhaust gas under low pressure at which water in the gas remains in the vapor phase; a second cell of equal sensitivity to said first cell and in opposing relation thereto in said bridge, and means for supplying it with atmospheric air at said low pressure, whereby said second cell neutralizes the effect on said bridge of atmospheric humidity in said first cell; a third cell of approximately double the sensitivity of said second cell and in aiding relation therewith, and means for supplying exhaust gas to said third cell at a pressure such that water saturation exists therein; and a fourth cell of equal sensitivity to and in opposing relation thereto said third cell, and means for supplying atmospheric air saturated with water vapor to said fourth cell; whereby the effect of said third cell neutralizes the effect of carbon dioxide in said first cell and substitutes the same effect in additive relation to the effect of water vapor in said first cell, and the effect of said fourth cell neutralizes the effect of water vapor in said third cell.

3. In thermal-conductivity apparatus comprising a bridge circuit, the improvement which comprises: a first cell of unit sensitivity mounted in one arm of said bridge circuit; means for supplying to said first cell exhaust gas under low pressure at which water in the gas remains in vapor phase; a second cell of double sensitivity in another arm of the bridge; means for supplying said second cell with exhaust gas at a high pressure at which the gas is saturated with

water vapor; and means for neutralizing the effect on said bridge circuit of water vapor in said second cell, whereby said bridge circuit is rendered additively responsive to water and carbon dioxide in said exhaust gas, said last mentioned means comprising a third cell of double sensitivity in said one arm of the bridge, said third cell containing atmospheric air saturated with water vapor; and means for maintaining the temperature of gas in said second and third cells the same.

4. In apparatus for analyzing exhaust gas resulting from combustion of a hydrocarbon fuel with air, the combination which comprises four thermal conductivity cells each including a resistor mounted therein, each of said resistors having an electrical conductivity varying with the composition of the gas supplied to the cell in which it is mounted, the first and second thermal conductivity cells being of one sensitivity and the third and fourth conductivity cells being of twice that sensitivity, means for supplying a portion of said exhaust gas to said first cell at a pressure low enough to maintain all water in said exhaust gas in the vapor phase; means for supplying air at the said low pressure to said second cell; means for supplying a portion of said exhaust gas to said third cell at a pressure high enough to produce water vapor saturation therein; and means for supplying air saturated with water vapor to said fourth cell; and means for measuring the difference between the sum of the resistances of the first and fourth cells and the sum of the resistances of the second and third cells.

5. In apparatus as defined in claim 4 means for treating said exhaust gas with a solid oxidizing agent to convert all carbon and hydrogen therein to carbon dioxide and water vapor prior to supplying said portions of exhaust gas to said first and second cells.

6. In apparatus for analyzing exhaust gas resulting from combustion of a hydrocarbon fuel with air, the combination which comprises two pairs of conductivity cells, each including a resistor mounted therein, each of said resistors having an electrical conductivity varying with the composition of the gas supplied to the cell in which it is mounted; means for supplying said mixture and a reference gas to the respective cells of one pair of cells at a relatively low pressure at which a condensable component in said exhaust gas remains in vapor phase; means for supplying said mixture and said reference gas to the respective cells of the other pair of said cells at a relatively high pressure; means for maintaining the vapor pressure of said condensable component equal in the cells of said second pair; and means interconnecting said resistors for measuring a combination of the resultant effects of said gases on the resistors in said cells.

7. In thermal conductivity apparatus for determining the composition of exhaust gas that is at a high temperature and at a relatively high pressure and that contains moisture in such an amount that the moisture would condense at such pressure at atmospheric temperature, the improvement which comprises a bridge circuit including first and second cells in adjacent arms thereof, said cells being exposed to atmospheric temperature, means for supplying such exhaust gas from a source to said first cell, said means including means for reducing the pressure of

11

the gas supplied to a relatively low value, whereby water therein remains in vapor phase; and means for supplying atmospheric air at a pressure of said value to said second cell, whereby the effect of atmospheric humidity in exhaust gas formed by combustion of fuel with atmospheric air is neutralized.
